FIG. II.

FIG. III.

FIG. IV.

FIG. V.

INVENTOR

Edwin M. Rosenbluth,

By *Arthur E. Haig,*
ATTORNEY

UNITED STATES PATENT OFFICE.

EDWIN M. ROSENBLUTH, OF WALLINGFORD, PENNSYLVANIA.

LANTERN.

1,351,067.

Specification of Letters Patent. Patented Aug. 31, 1920.

Application filed September 18, 1918. Serial No. 254,540.

To all whom it may concern:

Be it known that I, EDWIN M. ROSENBLUTH, a citizen of the United States, residing at Wallingford, in the county of Delaware and State of Pennsylvania, have invented a certain new and useful Improvement in Lanterns, whereof the following is a specification, reference being had to the accompanying drawings.

10 My invention relates to lanterns adapted to burn a liquid fuel, such as kerosene or other hydrocarbons, and of the class wherein the fuel is supplied in a lamp body, provided with a wick and shaft for operating it; such lamp body being separable from the lantern casing and requiring means to detachably secure it in coöperative relation in such casing, which includes a lamp chamber, a flame chamber, and a 15 chimney for the products of combustion. My improvements relate particularly to means appurtenant to such a lantern casing; whereby such a lamp body may be detachably locked in coöperative relation with said casing, prevented from accidental displacement and prevented from rattling, and include a removable cap for said lamp chamber; and means whereby said cap may be detachably locked in connection with said 20 casing, to maintain said lamp in coöperative relation therewith; but permitting said cap to be manually unlocked, for the removal of said lamp body to replenish it with fuel; such means including an inwardly extending flange adapted to be engaged by opposite projections upon the lamp casing; said flange having a single notch through which one of said studs may pass and having, adjacent that notch, an inwardly and down- 25 wardly extending stop projection on the cap, adapted to hold the cap with said notch out of registry with said projection.

Although I find it convenient to illustrate my invention with reference to a lantern 30 designed for attachment to a vehicle, it is to be understood that it is not restricted to such use, but that my invention includes the various novel features of construction and arrangement hereinafter more definitely specified.

In said drawing; Figure I is a side elevation of a lantern conveniently embodying my invention.

Fig. II is a vertical central sectional view of said lantern showing the coöperative relation of the casing, lamp body and cap.

Fig. III is a plan view of the bottom cap of said lantern casing shown in Figs. I and II.

Fig. IV is a sectional view of said cap, in the same plane as Fig. II, but detached from the lantern casing.

Fig. V is a sectional view similar to Fig. IV, but showing a modified form of cap.

Referring to said Figs. I to IV inclusive, the lantern casing 1 includes the lamp chamber 2 and the flame chamber 3 with the partition 4 between them, and said flame chamber is provided with the chimney 5 having suitable vents 6 for products of combustion. Said casing is provided with a system of air inlets and passageways, coöperative with said vents 6, and including the single wick shaft slot 7 and a plurality of air inlets 8 in the side wall of said lamp chamber, and the air flue 9 which affords a passageway through said partition 4, in the center of said lamp chamber. Said casing 1 is adapted to coöperate with the removable lamp comprising the body 10 and cap 11. Said body 10 is a reservoir for kerosene or other liquid hydrocarbon, and the detachable screw cap 11 is removably fitted in said body 10. Said lamp carries, on its cap 11, the perforated air screen 12 between said air inlets 8 and said air flue 9, which serves to equally distribute the air supply throughout its circumference. Said lamp cap has the wick tube 13 extending into said flame chamber 3, through said air flue 9, and has the wick shaft 14 extending to the exterior of said casing 1 through said wick shaft slot 7. Said shaft is journaled in said cap 11 and provided with the usual toothed wheels for engaging the wick 16.

The proper position of said lamp in said casing, which must be maintained, in order to render said lamp coöperative with said casing and the air circulating system thereof, is precisely predetermined by the vertical extent of said wick shaft slot 7. In order to maintain said lamp in the operative position shown in Fig. II, I find it convenient to provide diametrically opposite projections 17 at the lower edge of said casing 1, for detachable engagement with the bottom cap 18. Said cap 18 is formed of a single piece of resilient sheet metal having a unitary spring bottom 19 with a raised central portion 20 to uphold said lamp, by pressure upon the bottom of said lamp body 10. Said cap has the inwardly turned an-

nular spring flange 22 with the notch 23 to pass one of said projections 17, but is adapted to overhang both said projections 17. I provide the inwardly and downwardly extending stop projection 25 on said cap, at one side of said notch 23, to hold said cap with said notch 23 out of registry with said projection. That projection 25 is conveniently formed by downwardly turning the portion of the metal of said flange 22 which has been punched out to form said notch 23; which portion is preferably soldered to the cylindrical side wall of said cap. I provide the inwardly and downwardly extending locking projection 26, on said spring cap flange 22, to snap over one of said projections, as the cap is turned toward said stop 25, and thus pocket that projection 17 of the casing 1, between said projections 25 and 26 of the cap, to prevent accidental rotation and release of the latter; whereby said lamp may be locked in operative relation with said casing 1, prevented from accidental displacement, and prevented from rattling, by said cap 18, which thus resiliently holds said lamp, until said cap is manually turned to the position in which it may be removed from said casing.

It is to be understood that said cap may be applied to said casing by engaging the unnotched portion of its spring flange 22 over one of said projections 17, with the cap inclined as indicated in dotted lines in Fig. I; the notch 23 in said flange being in registry with the opposite casing projection 17 so that the cap may be swung up to the position shown in full lines in Figs. I and III, in which latter position, the cap may be turned to overhang and engage both casing projections 17. In order to lock said cap in engagement with said casing, in that position, in which the lamp is in operative correlation with the casing; said cap is then turned until the locking projection 26 snaps over one of said casing projections 17 and pockets the latter between said projections 25 and 26 on said cap, as indicated by the dotted circle in Fig. IV. To unlock said cap and release said lamp, it is necessary to rotate it in the opposite direction, until its notch 23 registers with one of said casing projections 17, when the cap may be lowered to the position shown in dotted lines in Fig. I and laterally removed from the other casing projection 17, which thus serves as a hinge for said cap both in opening and closing the latter with respect to said casing 1.

In the form of my invention shown in Fig. V; I dispense with the inwardly and downwardly extending stop projection 25 on the cap 28, and provide the latter with two locking projections 29 (which are each like the locking projection 26 aforesaid) on respectively opposite sides of the notch 30,

which is shaped like the notch 23 in said cap 18. In this form of my invention; the cap 28 may be applied to the casing 1 precisely like the cap 18, as above described, but may be locked in connection with the casing, by turning it in either direction, to cause either one of said locking projections 29 to snap over the casing projection 17 which has just come through the cap notch. That modified form of my invention is cheaper to manufacture than the form including said stop 25, but is less secure than the latter, because the cap may be released by turning it in either direction to cause either cap projection 29 to snap over a casing projection 17 to permit the latter to register with the notch 30; whereas, in the form including said stop 25, it is impossible for the cap stop projection 25 to be turned past the casing projection 17, and it is therefore necessary to turn the cap a half revolution to remove it from its locked position.

It may be observed that the general construction of the lantern shown in the drawings is substantially such as shown in Letters Patent of the United States No. 609,588 granted to the present applicant August 23, 1898, with the exception of the bottom cap on the lamp casing. A very large number of lanterns having caps such as shown in said Letters Patent having been made and used, it appeared that, first, as the springs in said caps were made separate and distinct therefrom and soldered thereto, the soldering operation so far reduced the resiliency of the spring metal that the springs were readily distorted from their proper initial form and thereafter permitted greater freedom of vibration of the cap than was intended and, second, because such caps did not have any means for locking them in assembled position; the vibration to which they were subjected in connection with the vehicle frequently sufficed to loosen them so that they would fall off, thus permitting the lamp itself to fall out of the casing and be lost, while the vehicle carrying the lamp was moving, and without attracting the attention of its operator. Therefore, my present invention is advantageous in that it not only overcomes both of the aforesaid difficulties, but by a construction which is less costly to manufacture, both as to materials and labor, than the cap and spring shown in said Letters Patent.

I do not desire to limit myself to the precise details of construction and arrangement herein set forth, as it is obvious that various modifications may be made therein without departing from the essential features of my invention as defined in the appended claims.

I claim:

1. In a lantern, the combination with a casing, including a lamp chamber in the

- lower portion thereof; of a lamp in said chamber; diametrically opposite projections at the lower edge of said casing; a bottom cap for said casing, formed of a single piece 5 of resilient sheet metal, having a unitary spring bottom with a raised central portion to uphold said lamp, and an inwardly turned annular spring flange, having a notch to pass one of said projections, but adapted 10 to overhang and engage both said projections; an inwardly and downwardly extending stop projection on said cap at one side of said notch; and an inwardly and downwardly extending locking projection on said flange; whereby said lamp may be locked in coöperative relation 15 with said casing, prevented from accidental displacement, and prevented from rattling, by said cap.
2. In a lantern, the combination with a casing, including a lamp chamber in the lower portion thereof; of a lamp in said chamber; diametrically opposite projections at the lower edge of said casing; a bottom cap for said casing, formed of a single piece 20 of resilient sheet metal, having a unitary spring bottom with a raised central portion to uphold said lamp, and an inwardly turned annular spring flange, having a notch to pass one of said projections, but adapted 25 to overhang and engage both said projections; an inwardly and downwardly extending locking projection on said flange; whereby said lamp may be locked in coöperative relation 30 with said casing, prevented from accidental displacement, and prevented from rattling, by said cap.
3. In a lantern, the combination with a casing, including a lamp chamber in the lower portion thereof; of a lamp in said chamber; diametrically opposite projections at the lower edge of said casing; a bottom cap for said casing, formed of a single piece 35 of resilient sheet metal, having an inwardly turned annular spring flange, having a notch to pass one of said projections, but adapted 40 to overhang and engage both said projections; an inwardly and downwardly extending locking projection on said flange; whereby said lamp may be locked in coöperative relation 45 with said casing, prevented from accidental displacement, and prevented from rattling, by said cap.
4. In a lantern, the combination with a casing, including a lamp chamber in the lower portion thereof; of a lamp in said chamber; diametrically opposite projections at the lower edge of said casing; a bottom cap for said casing, having a unitary spring bottom 50 with a raised central portion to uphold said lamp, and an inwardly turned annular spring flange, having a notch to pass one of said projections, but adapted 55 to overhang and engage both said projections; an inwardly and downwardly extending locking projection on said flange; whereby said lamp may be locked in coöperative relation 60 with said casing, prevented from accidental displacement, and prevented from rattling, by said cap.
5. In a lantern, the combination with a casing, including a lamp chamber in the lower portion thereof; of a lamp in said chamber; diametrically opposite projections at the lower edge of said casing; a bottom cap for said casing, having an inwardly turned annular spring flange, having a notch to pass one of said projections, but adapted 65 to overhang and engage both said projections; an inwardly and downwardly extending stop projection in said cap adjoining said notch; and an inwardly and downwardly extending locking projection on said cap; whereby said lamp may be locked in coöperative relation 70 with said casing, prevented from accidental displacement, and prevented from rattling, by said cap.
6. In a lantern, the combination with a casing, including a lamp chamber in the lower portion thereof; of a lamp in said chamber; diametrically opposite projections at the lower edge of said casing; a bottom cap for said casing, having an inwardly turned annular spring flange, having a notch to pass one of said projections, but adapted 75 to overhang and engage both said projections; an inwardly and downwardly extending stop projection in said cap adjoining said notch; and one inwardly and downwardly extending locking projection on said cap; whereby said lamp may be locked in coöperative relation 80 with said casing, prevented from accidental displacement, and prevented from rattling, by said cap.
7. In a lantern, the combination with a casing; of a lamp removably fitted in said casing; opposite projections at the lower edge of said casing; a bottom cap for said casing, formed of a single piece of resilient sheet metal, having a unitary spring bottom 85 with a raised central portion to uphold said lamp, and an inwardly turned annular spring flange, having a notch to pass one of said projections, but adapted 90 to overhang and engage both said projections; and two inwardly and downwardly extending projections on said cap; whereby said lamp may be locked in coöperative relation 95 with said casing, prevented from accidental displacement, and prevented from rattling, by said cap.
8. In a lantern, the combination with a casing; of a lamp removably fitted in said casing; opposite projections at the lower edge of said casing; a bottom cap for said casing, formed of a single piece of resilient sheet metal, having an inwardly turned an- 100

5 nular spring flange, having a notch to pass one of said projections, but adapted to overhang and engage both said projections; an inwardly and downwardly extending stop projection in said cap at one side of said notch; and an inwardly and downwardly extending locking projection on said flange; whereby said lamp may be locked in coöperative relation with said casing, prevented 10 from accidental displacement, and prevented from rattling, by said cap.

9. In a lantern, the combination with a casing; of a lamp removably fitted in said casing; opposite projections at the lower 15 edge of said casing; a bottom cap for said casing, formed of a single piece of resilient sheet metal, having an inwardly turned annular spring flange, with a notch to pass one of said projections, but adapted to overhang 20 and engage both said projections; and two inwardly and downwardly extending projections in said cap, adjacent said notch; whereby said lamp may be locked in coöperative relation with said casing, prevented 25 from accidental displacement, and prevented from rattling, by said cap.

10. In a lantern, the combination with a casing; of a lamp removably fitted in said casing; opposite projections at the lower 30 edge of said casing; a bottom cap for said casing, having an inwardly turned annular flange, with a notch to pass one of said projections, but adapted to overhang and engage both said projections; an inwardly and 35 downwardly extending stop projection in said cap at one side of said notch; and an inwardly and downwardly extending locking projection on said flange; and a spring element in unitary relation with said cap, arranged to uphold said lamp; whereby said 40 lamp may be locked in coöperative relation with said casing, prevented from accidental displacement, and prevented from rattling, by said cap.

45 11. In a lantern, the combination with a casing; of a lamp removably fitted in said casing; opposite projections at the lower edge of said casing; a bottom cap for said casing, having an inwardly turned annular 50 spring flange, having a notch to pass one of said projections, but adapted to overhang and engage both said projections; two in-

wardly and downwardly extending projections in said cap; and a spring element in said cap, arranged to uphold unitary relation with said lamp; whereby said lamp may be locked in coöperative relation with said casing, prevented from accidental displacement, and prevented from rattling, by 55 said cap.

12. In a lantern, the combination with a casing, having an opening, with projections at opposite sides thereof; of a cap for said opening, formed of a single piece of resilient sheet metal, having an inwardly turned annular spring flange, with a notch to pass one of said projections, but adapted to overhang and engage both said projections; an inwardly extending stop projection in said cap at one side of said notch, formed of the metal from said notch, in unitary relation with said cap, at one end, and soldered to said cap, at the other end; and an inwardly extending locking projection on said flange, whereby said cap may be locked on said 75 casing.

13. In a lantern, the combination with a casing, having an opening, with projections at opposite sides thereof; of a cap for said opening, having a notch to pass one of said 80 projections, but adapted to overhang and engage both said projections; an inwardly extending stop projection in said cap at one side of said notch, formed of the metal from said notch, in unitary relation with said 85 cap; and an inwardly extending locking projection on said flange; whereby said cap may be locked on said casing.

14. In a lantern, the combination with a casing, having an opening, with projections at opposite sides thereof; of a cap for said opening, having an inwardly turned flange, with a notch to pass one of said projections, but adapted to overhang and engage both 90 said projections; and two inwardly extending projections on said cap; whereby said cap may be locked on said casing.

In testimony whereof I have hereunto signed my name at Philadelphia, Pennsylvania, this tenth day of September, 1918.

EDWIN M. ROSENBLUTH.
